UNITED STATES PATENT OFFICE.

HARRY DAVIDSON, OF NEW YORK, N. Y., ASSIGNOR OF ONE-HALF TO
ALFRED C. CLAPP, OF SAME PLACE.

DESIGN FOR A HOOK.

SPECIFICATION forming part of Design No. 23,656, dated September 25, 1894.

Application filed August 9, 1894. Serial No. 519,884. Term of patent 14 years.

To all whom it may concern:

Be it known that I, HARRY DAVIDSON, a citizen of the United States, residing at New York, in the county of New York and State 5 of New York, have invented and produced a new and original Design for Hook-and-Eye Fastenings, of which the following is a specification, reference being had to the accompanying drawings, showing a part thereof.

- Figure 1 is a perspective view of the hook. Fig. 2 is a top plan view thereof.

The design is for a hook formed of a single wire, having a central return bend forming the hook shank, and its ends on opposite sides 5 of the shank are bent into S-shaped stays and their extremities pointed. The stays extend collateral with the shank and lie sub-

stantially in the same plane therewith and with each other, their pointed ends facing in opposite directions. Furthermore the shank 20 is slightly curved near its rear end in a plane substantially perpendicular to the plane of the S-shaped ends or "stays."

What I claim is—

The design for a hook, substantially as set 25 forth.

In testimony that I claim the foregoing as my own I affix my signature in presence of two witnesses.

HARRY DAVIDSON.

In presence of—

WALTER C. PHELPS,
FREDERICK LANGFIELD, Jr.
